No. 818,859.

PATENTED APR. 24, 1906.

H. W. ADAMS.
FEED WATER REGULATOR.
APPLICATION FILED MAY 10, 1905.

UNITED STATES PATENT OFFICE.

HARRY WALTER ADAMS, OF FARGO, NORTH DAKOTA, ASSIGNOR OF ONE-HALF TO PHILIP W. FARNHAM, OF FARGO, NORTH DAKOTA.

FEED-WATER REGULATOR.

No. 818,859.

Specification of Letters Patent.

Patented April 24, 1906.

Application filed May 10, 1905. Serial No. 258,693.

To all whom it may concern:

Be it known that I, HARRY WALTER ADAMS, a citizen of the United States, and a resident of Fargo, in the county of Cass and State of North Dakota, have invented a new and Improved Feed-Water Regulator, of which the following is a full, clear, and exact description.

My invention relates to apparatus for regulating the supply of water to boilers, and has for its principal objects the provision of an effective regulator with which gage devices and high and low water signals may be combined.

It consists in the various features and combinations hereinafter described and more particularly claimed.

Reference is to be had to the accompanying drawing, illustrating one embodiment of my invention.

I have here shown a casing A having a main or body portion 10, one end of which is closed by a plate 11 and at its other end tapering outwardly to a head or enlargement 12. This head is provided with a downward extension 13 and an opposite upward extension 14, this latter having an opening which is closed by a plate 15. In the extensions 13 and 14 are water and steam openings 16 and 17, respectively, situated at one side and near the extremities of these portions of the head. Between the steam and water openings are shown three openings 18 to receive the usual gage-cocks, and at the outer side 35 of the head opposite the main portion of the casing are openings in which are inserted the connections for a gage-glass 19. In the bottom of the extension 13 is an opening in which is set a blow-off cock 19a.

Extending inwardly from the plate 11 is a bracket 20, upon which is fulcrumed a lever 21, one arm of which extends toward the casting-head and has fixed to it a float 23, here illustrated as of spherical form. This float 40 preferably carries upon its under side a plate 24, which projects beyond the adjacent curved wall of the float and being immersed in the water entering the casing through the opening 16 serves to steady the float and retain it against jumping or churning under the action of the feed-pump. Above the fulcrum of the lever rises an arm 25, which has pivoted to it a member 26, mounted to

slide in a recess in a guide projection 27 from the plate 11 above the bracket. From the 55 end of the member within this recess opens a threaded bore 28, which receives a similarly-threaded stem 29. This stem extends through a bore in the plate 11, in which it fits, into a valve-casing 30, which is conveniently supported upon the outer side of the plate. The valve-casing has connected with it inlet and outlet pipes 31 and 32, respectively, which lead from a source of water under pressure, as that supplied by a pump and 60 to the boiler. Between the inlet and outlet of the valve-casing is a partition 32a, in which are opposite cylindrical guides 33 33. Through these guides moves a valve-body 34, surrounding the stem 29 and being fixed 65 between a collar 34a, fast thereon, and nuts 34b, threaded upon the stem. In the portions of the valve-body operating in the guides are longitudinal grooves or passages 35, through which, when the body is moved to the right 70 the liquid may flow from the supply-pipe through the feed-pipe to the boiler. At the outer side of the valve-casing is a stuffing-box 36, through which passes a section 37 of the stem 29, this section having upon its outer 75 extremity a handle 38. Within the valve-casing it is slotted at 39, and into these slots project pins 40, carried by the adjacent end of the stem 29. This allows the valve to be moved by the float-lever without affecting 80 the stem-section 37. At the same time a sufficient movement of this section will reciprocate the stem 29, and its rotation will 85 also turn said stem.

When the water within the casing A is at 90 its normal level or in proximity to the opening for the center gage-cock, the valve will be held by the float-lever with its passages closed, thus shutting off communication between the supply-pipe and feed-pipe. When 95 the level of the water falls to such an extent that the admission of a further supply is desirable, the lever-arm 25, which has been moved outwardly by the fall of the float-arm, acts, through the member 26 and the connected stem, to so move the valve-body that its 100 passages are open and water is admitted to the boiler. If the level thus secured is not the proper one, the relation between the float-lever and the valve may be changed by rotating the stem-section 37 through its handle 105

This, by virtue of the thread, shifts the member 26 along the stem, causing the valve to become effective upon a greater or less fall of the float. If the valve should become stuck 5 in its guides, the stem-section 37 can be moved back and forth sufficiently to bring the ends of the slots into contact with the pins 40, thus exerting a more positive effect to free it.

- 10 In the plate 15 is an opening threaded to receive the end of a small casing 41, rising above the head of the main casing. This carries a signal, which is preferably audible, and is here shown as in the form of a whistle 15 42. Within the casing 41 operates a valve 43, held to its seat by a spring 44, situated between the valve and nuts 45, threaded into the interior of the casing. These nuts have axial openings 46 to receive and guide the 20 stem 47 of the valve. This stem at the opposite side projects into the casing-head, where it contacts with a lever 48, fulcrumed upon the plate 15 and having an arm 49 depending somewhat below the steam-opening. 25 At one side the lever has an extension 50, upon which is hung a rod 51, supported by nuts 52, threaded upon the rod above the extension, and having its lower extremity situated just above the water-opening. Here 30 the rod is hooked at 53, and between this hooked end and the arm 49 of the lever moves a float 54, conveniently of spherical form and prevented from passing into the main portion of the casing A by the rod 51. 35 For the normal water-level or conditions not far removed from this the float 54 is supported by the liquid in the casing-head out of contact with both the lever-arm 49 and the hook 53. If, however, the level rises or falls 40 to such an extent that it approaches either the steam or water opening, the float is brought into contact with the lever-arm or the hook. In the former instance it raises the arm by its buoyancy and swings the lever 45 upon its fulcrum to lift the stem 47, thus opening the valve and sounding the whistle. In event of the water falling, the weight of the float rests upon the hooked end of the rod, which operating through the lever extension 50 moves the stem upwardly and similarly opens the valve and gives an alarm.

Having thus described my invention, I claim as new and desire to secure by Letters Patent—

- 55 1. A feed-water regulator comprising a casing, a valve associated with the casing, a float movable in the casing, an adjustable connection between the valve and float, and means operable from the outside of the casing for 60 operating the valve and adjusting the connection between said valve and float.

2. A feed-water regulator comprising a casing, a valve associated with the casing, a lever fulcrumed in the casing, a float carried by the

lever, a sliding member to which the lever is 6 pivoted, and a rotatable valve-stem threaded into the sliding member.

3. A feed-water regulator comprising a casing, a valve associated with the casing, a lever fulcrumed in the casing, a float carried 7 by the lever, and a valve-stem having independently-movable sections, one of which is adjustably connected with the said lever.

4. A feed-water regulator comprising a casing, a valve associated with the casing, a float 7 movable in the casing and being connected with the valve, and a plate secured to the lower face of the float and extending beyond the adjacent surface thereof.

5. A feed-water regulator, comprising a 8 main casing having an inwardly-extending tubular projection, a lever fulcrumed in the casing and carrying a float, a member slideable in the tubular projection of the casing and with which the float-lever is pivotally 8 connected, a valve-casing at one end of the main casing and having an inlet and outlet, and a valve in the valve-casing and having its stem projecting into the tubular projection of the main casing and secured to the 9c said sliding member.

6. A feed-water regulator, comprising a main casing having an inwardly-extending tubular projection, an elbow-lever fulcrumed in the casing and provided with a float on one 95 member, a member sliding in the tubular extension of the casing and to which the other member of the elbow-lever is pivoted, said sliding member having a threaded bore in its inner end, a valve-casing at one end of the 10 main casing, a valve in the valve-casing, and a stem having its end threaded and projecting into the tubular projection of the main casing and screwing into the bore of the sliding member.

7. In a feed-water regulator, a main casing, a lever fulcrumed in the casing and carrying a float, a valve-casing, a valve in the casing, and a valve-stem formed of sections having a sliding connection with each other, one section 11 extending into the main casing and pivotally connected with the float-lever and the other section extending out through the valve-casing and provided with a handle.

8. In a feed-water regulator, a main casing having an inwardly-extending tubular projection, a lever fulcrumed in the casing and carrying a float, a valve-casing, a valve-stem formed of sections having a sliding connection with each other, one section 12 extending out through the valve-casing and provided with a handle, and the other extending into the tubular projection of the main casing, and a sliding member in the said tubular projection and into which the valve-stem screws. 12

9. In a feed-water regulator, a main casing, a lever fulcrumed in the casing and carrying a float, a valve-casing, a valve in the valve-

casing and having a stem formed of sections having a sliding connection with each other, one section extending out through the valve-casing and provided with a handle, and means for adjustably connecting the other valve-stem section with the said lever.

5 In testimony whereof I have signed my

name to this specification in the presence of two subscribing witnesses.
